UNITED STATES PATENT OFFICE.

JOHN BAJUS, OF CANAANVILLE, OHIO.

OIL-WELL GRAPPLE.

Application filed December 28, 1922. Serial No. 609,489.

To all whom it may concern:

Be it known that I, JOHN BAJUS, a citizen of the United States of America, residing at Canaanville, in the county of Athens and State of Ohio, have invented certain new and useful Improvements in Oil-Well Grapples, of which the following is a specification.

This invention relates to certain new and useful improvements in oil well grapples and is particularly designed for extracting broken pipes from oil or other wells.

The primary object of the invention resides in the provision of an oil well grapple wherein a tubular casing has an outwardly flared lower end for readily positioning the same upon a broken pipe section with means carried by the casing automatically moved into engagement with a broken pipe for gripping the same to remove the pipe from a well.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of an oil well grapple constructed in accordance with the present invention, a well casing and pipe being illustrated by dotted lines,

Figure 2 is a vertical sectional view of the grapple with a broken pipe section gripped therein and illustrated by dotted lines,

Figure 3 is a cross-sectional view taken on line III—III of Fig. 2 showing the pipe gripping arms extending into the grapple casing,

Figure 4 is a side elevational view, partly broken away and shown in section of the modified form of grapple wherein the pipe gripping arms are pivotally mounted in pivoted members carried by the grapple casing, and

Figure 5 is a cross-sectional view taken on line V—V of Fig. 4.

Referring more in detail to the accompanying drawing, there is illustrated a grapple especially designed for extracting broken pipes from oil or other wells, the

grapple including, as illustrated in Figs. 1 to 3, a tubular casing 1 having an outwardly flared lower end 2 with a shackle 3 removably secured to the upper end thereof to which a hoisting cable 4 is attached. As shown in Fig. 1, the grapple is illustrated as operatively positioned in a well having a casing pipe 5 and a pipe section 6 working therein.

As shown more clearly in Figs. 2 and 3, the tubular casing 1 intermediate the ends thereof is provided with circumferentially arranged and equi-distantly spaced outwardly directed sections, each embodying side walls 7 and an outer wall 8, the lower end 9 of the outer wall being inclined downwardly toward the wall of the casing 1 while the upper ends of the side walls 7 are cut-away as at 10. A gripping arm 11 is pivotally mounted as at 12 in each section adjacent the lower end thereof and is engaged at its upper side by the leaf spring 13 secured as at 14 to the outer wall 8, the openings 10 facilitating access to the arms 11 and spring 13 for purposes of repair or otherwise. The working ends of the arms 11 are serrated as at 15 for more positively gripping a pipe section 6 as illustrated in Fig. 2.

In the operation of the device, the arms 11 are normally positioned at their limit of downward movement in engagement with the inclined wall 9 of each section and the grapple casing 1 is lowered into a well as shown in Fig. 1 by the cable 4. The outwardly flared lower end 2 of the grapple casing facilitates positioning thereof upon the pipe section 6, the upper end of which engages the arms 11 to move the same upon the pivot pins 12 into the position shown in Fig. 2, upward movement of the grapple casing 1 causing the serrated working edges 15 of the arms 11 to positively grip the pipe section 6 and be retained in engagement therewith by the springs 13, as well as wedging action for removing the broken pipe sections from the well.

In the form of the invention shown in Figs. 4 and 5, the sections housing the arms 12 are formed separately from the grapple casing 1, the same being hinged at their upper ends at 16 to the grapple casing, while the lower ends thereof are removably bolted as at 17 to the casing 1, the gripping arms 11 and springs 13 being carried by the hinged

sections and projecting through side openings 18 in the grapple casing when positioned as illustrated in Fig. 4.

While there are herein shown and described the preferred embodiment of the present invention, it is nevertheless to be understood that minor changes may be made therein without departing from the spirit and scope thereof as claimed.

10 10 What is claimed as new is:—

In an oil well grapple, a tubular casing having an outwardly flaring lower end, suspending means for the casing, said casing having a series of circumferentially arranged longitudinal 15 extending equi-distantly spaced openings formed therein, a housing member pivotally secured to the outer wall of the

casing in proximity to the upper end of each opening adapted to cover the same, said members each having a downwardly inclined lower end wall, a gripping arm pivotally mounted in each member adjacent its lower end adapted to normally rest upon said lower inclined wall, a spring element engaging each gripping arm forcing downwardly thereon, and means for securing the lower ends of the housing members to the casing wall so that said gripping arms will normally extend downwardly into said casing through said openings with their outer 30 ends positioned in proximity to each other.

In testimony whereof I affix my signature.

JOHN BAJUS.
